UNITED STATES PATENT OFFICE.

PAUL HÉROULT, OF NEUHAUSEN, SWITZERLAND, ASSIGNOR TO THE UNITED STATES ALUMINIUM METAL COMPANY, OF NEW YORK.

ELECTRODE FOR USE IN ELECTRO-METALLURGICAL PROCESSES.

SPECIFICATION forming part of Letters Patent No. 473,117, dated April 19, 1892.

Application filed September 3, 1889. Serial No. 322,878. (No specimens.) Patented in England December 7, 1887, No. 16,853.

To all whom it may concern:

Be it known that I, PAUL HÉROULT, a citizen of the Republic of France, residing at Neuhausen, in the Republic of Switzerland, have invented a certain new and useful Improvement in Electrodes for Use in Electro-Metallurgical Processes, (for which I have obtained Letters Patent of Great Britain No. 16,853, dated December 7, 1887,) of which the following is a specification.

My invention relates to an improved electrode which has been designed with especial reference for use in certain electrolytical processes for the reduction of aluminium, silicon, or other metals from their refractory oxides, but which may be employed for various other electro-metallurgical or electro-chemical processes as well; and its object is to render possible the concentration of the electric energy at the point of the electrode without wasteful expenditure thereof arising from the resistance of the electrode.

The general character of my improvements may be outlined by noting that the electrode is composed, mainly, of carbon, but has combined therewith a metal which shall be one or more of the normal constituents of the useful product of the operation, and that the carbon of the electrode consists either of a single block or of a plurality of strips or rods, which may be secured together in a number of different ways—as, for instance, by casting a metal around them or by clamps or locking-pins.

My invention is illustrated in the accompanying drawings, wherein—

Figure 1 is a longitudinal sectional view of one form of my invention. Fig. 2 is a perspective view of a modified form. Fig. 3 is a plan view of still another modification, and Fig. 4 is a sectional view of the electrode and crucible in position for operation.

In all the figures the body of the electrode consists of carbon, and its resistance is reduced by combining a metal therewith. This is accomplished in the form shown in Fig. 1 by preparing a block of carbon for baking with a core passed through its center, where-by the carbon A will, when cool, have a central opening B extending therethrough. Lat-50 eral holes b are then bored in the carbon

block and the whole is filled with cast metal, such as copper or iron.

In Fig. 2 the electrode consists of a number of carbon slabs C, arranged side by side and secured together by two plates of metal c c' 55 on the outside of the carbon slabs, which are clamped by clamps e e', the lower one e' being adjustable lengthwise of the electrode. A metal plate, as d', may also be placed in the center of the carbon, or the outside metal 60 plates may be dispensed with and the central one alone employed.

In Fig. 3 the electrode consists of four carbon rods D, arranged as shown and secured together with cast metal F, which surrounds 65 and fills up the interstices between the rods.

An electrode formed in any of the different ways explained above is adapted for use in combination with a crucible, such as in Fig. 4, containing an electrolyte adapted to be reduced by the action of an electric current in accordance with the process described in my patent, No. 387,876, granted August 14, 1888, or other metallurgical processes involving the use of an electric current. In this figure 75 D' is the crucible, E is a refractory oxide, and E' is a metal to be alloyed therewith. G is the electrode, serving herein as the anode, and H I are the electrical connections which complete the circuit from a suitable source of 80 electricity to the metal combined with the anode, and thence to the electrolyte and the cathode, as is apparent from the drawings.

The electrode being used in combination with a crucible for the reduction of ores, it is 85 essential that the metal in the anode be the same as one or more of the normal constituents of the useful product of the desired operation, because the metal would otherwise commingle with the elements of the bath and 90 form an impurity in the product. Thus if an aluminium bronze is to be formed the metal in the electrode may be either copper or aluminium or aluminium bronze while if a ferro-aluminium is the product desired the 95 metal in the electrode will be either iron or aluminium or ferro-aluminium, and if aluminium is to be formed by the reduction of any of its compounds the metal of the electrode should be aluminium. 100

The reduction of the resistance of the electrode is especially important in metallurgical operations of this character because electric currents of great quantity and small electro-motive force are used and the existence of an unnecessary resistance in the circuit, although actually small, would involve a large wasteful expenditure of energy.

- I claim as my invention—
- 10 1. An electrode for use in electro-metallurgical or electro-chemical processes, consisting of a plurality of carbon strips secured together in a single block and a metal combined therewith extending substantially the entire length
  - 15 of the electrode, whereby such metal is adapted to lower the electrical resistance of the electrode when in use.

2. An electrode for use in electro-metallurgical or electro-chemical processes, consisting of a plurality of carbon strips and a metal 20 cast around the strips and extending substantially the entire length of the electrode, whereby such metal holds the strips in place and lowers the electrical resistance of the electrode when in use.

25

In testimony that I claim the foregoing as my invention I have signed my name, in presence of two witnesses, this 16th day of August, 1889.

PAUL HÉROULT.
